Attorneys.

UNITED STATES PATENT OFFICE.

WILLIAM F. HUNT, OF NEW BRIGHTON, NEW YORK, ASSIGNOR TO THE OXWELD RAIL-ROAD SERVICE COMPANY, A CORPORATION OF DELAWARE.

OUTDOOR LAMP.

Application filed June 30, 1924. Serial No. 723,382.

This invention relates to outdoor lamps and particularly to a portable enclosed-flame acetylene lamp that is especially adapted for use by car inspectors and others employed about railroad equipment. However, it will be understood that features of the improved lamp may be embodied in other types of lamps and that this lamp is well adapted for general use, as in navigation and for signaling purposes, because its light penetrates rainy, foggy, smoky and similar atmospheres, and may be easily distinguished from other kinds of light.

Inasmuch as a satisfactory outdoor lamp must be capable of operating properly under all weather conditions, it is important that an outdoor acetylene lamp shall be weather-proof and that the gas flame thereof shall be so enclosed that it will stay lighted even in windy, rainy, or other adverse weather. Furthermore, for handling the lamp it is desirable that it shall be so constructed that it may be either carried by a bail, like the usual railroad lantern, or held by a rigid handle, so that the light therefrom may be reflected in any desired direction.

Accordingly, the objects of the present invention are to provide a suitable portable lamp fulfilling the foregoing requirements; to provide improved means comprising a fracture and high-temperature resistant cover glass for enclosing the flame of the lamp and protecting it from unfavorable weather conditions; and to provide improved carrying means for the lamp comprising a rigid handle and a bail pivoted thereon.

Fig. 1 is a plan view of a lamp embodying this invention;

Fig. 2 is a side view of the same, parts being shown in section; and

Fig. 3 is a perspective view of the handle of the lamp.

As shown in the drawings, the invention is applied to a familiar type of portable acetylene gas generator consisting of a water chamber *W* that has a threaded bottom end *W'* coupled to the threaded top end *C'* of a carbide chamber *C* that is provided with an enlarged base *C''*. The water chamber *W* contains a gas chamber *G* which receives acetylene from the carbide chamber and delivers the same through a pipe *P* to a burner tip *T*. The burner tip *T* may be of any suitable or preferred type that produces an open flame and, as shown, may have two

orifices *T'* delivering jets which impinge against one another to produce a fish-tail flame extending across the main axis of a parabolic reflector *R* which encloses said flame at the rear and sides.

The reflector *R* is mounted on a rigid handle *H* that is secured to the acetylene generator. The handle *H* consists of a stiff metal strip comprising two main parallel sections *H^a* and *H^b* and a third shorter substantially parallel section *H^c* connected to the lower end of the section *H^b* by a curved section *H^d* and extending upwardly between the main sections *H^a* and *H^b*. The sections *H^a* and *H^b* are united by a horizontal section *H^e*, and the sections *H^a* and *H^c* are brazed or otherwise secured to opposite or front and rear sides of the water chamber of the generator, as at *X* and *X'*. Below the brazing *X*, the handle section *H^a* is bent outwardly away from the generator on a curve as at *H'* to fit the outside of the reflector *R* and support the same. Registering holes *R'* and *P'* are provided in the reflector and the supporting section *H^f* for the pipe *P*. A plate *N* is secured by rivets *N'* to the upper side of the reflector and has a turned-up end secured at *N''* to the handle section *H^a*.

The front end of the reflector is closed by a curved lens or glass cover *L*, which preferably consists of a good quality of fracture-resistant and high-temperature-resistant glass, such as pyrex, that will withstand extreme differences of temperature between the inside and outside of the flame enclosure, as well as effects of rain, snow, etc., without fracturing. The flame from the tip is thus enclosed in a compartment formed by the reflector and the glass cover. The glass cover may be mounted as a door, by securing its periphery in a groove *L'* in the bezel or door frame *D* which has a hinge member *D'* riveted to its upper end and connected to a hinge projection *D''* at the outer end of the plate *N*. The door may be held in closed position by a spring latch *E* that has one end secured at *E'* to the reflector *R* and handle section *H^f*, and its free end provided with a hook *E''* adapted to latch over the edge of the ring *D*. Ventilating openings *R''* and a chimney *M* may be provided for the flame enclosure. The chimney may consist of a perforated metal tube that registers with registering apertures in the plate *N* and reflector *R*, being secured to the reflector by 110

rivets N', and provided with an imperforate flanged metal cap K held in place over its outer end by spring clips K' to exclude rain, snow, etc. The reflector, chimney and glass cover thus form a lamp house or inclosure for the burner.

A bail B is provided, in addition to the handle H, for carrying the lamp. The main handle sections H^a and H^b have alined openings therein to receive the bent ends B' of the bail, whereby the bail is swingable about an axis in the plane of the rigid handle H, either into a vertical position above the handle H or down into a position alongside the generator and the handle H, as shown in Figs. 1 and 2. In the folded-down position, the bail is close enough to the handle section H^b so that the latter and the adjacent part of the bail may both be gripped by the same hand. Offset projections B'' on the rear handle section H^b may be provided to hold the bail in its upright position, the bail springing past these projections when it is folded down intentionally. The handle section H^b is spaced from the rear of the gas generator so as to leave sufficient room there for part of the hand that grips this section of the handle. Suitable slots such as the keyhole openings H^o in the handle section H^b may be provided for hanging the lamp from a nail or the like.

The generator may be provided with suitable water feed-controlling and distributing devices, such as an outside controlled valve V which is adapted to turn a rod V' that extends through the water passage V'' and tube S into the carbide chamber and regulates the flow of water into the latter. A water distributing device S' may be loosely mounted on a button S'' carried by the end of the rod V'. The gas generated may pass through openings F' and a filter F into the gas chamber. The water control valve V is in the plane of the handle H but the handle section H^a is spaced far enough from the valve V so that the latter, as well as the water filling cap W', are easily accessible.

While the improved lamp is shown and described in detail, it will be understood that various changes may be made in the construction without departing from the spirit of the invention.

I claim:

1. In a portable lamp, the combination of a case carrying lighting means at the front side thereof, a handle for said lamp secured to the front and rear sides of said case and having sections thereof spaced from the top and rear side of said case, and a bail connected to said handle and foldable down alongside said case.

2. In a portable gas lamp, the combination of a gas generator, a burner tip communicating with the gas chamber of said generator and disposed at the front side thereof,

a handle for said lamp secured to the front and rear sides of said generator and having portions thereof spaced from the top and rear side of said generator, and a bail connected to said handle, said bail being swingable about an axis in the plane of said handle into operative position above said handle and into inoperative position alongside said generator and handle. 70

3. In a portable lamp, the combination of a gas generator; a burner tip communicating with the gas chamber of said generator; a rigid handle for said lamp comprising three substantially parallel sections, two of which are respectively secured to the front and rear sides of said generator, the third being spaced from the rear side of said generator; and a bail pivotally connected to such front and third parallel sections of the handle and arranged so that its free end is swingable into operative position above said handle and into inoperative position alongside said generator. 80

4. In a portable lamp, the combination of a case carrying lighting means; a handle for said lamp comprising a metal strip secured to the front and rear sides of said case, said strip extending outwardly from said case below its connection thereto; and a reflector mounted on such outwardly extending part of the handle strip. 90

5. The invention defined in claim 4, in combination with a hinged glass cover for said reflector, and a latch for said cover secured to such outwardly extending part of the handle strip. 100

6. In a portable gas lamp, the combination of a gas generator, a handle for said lamp comprising a metal strip secured to the generator and having an apertured section extending outwardly from the front of the generator, a reflector secured to such outwardly extending section, and having an aperture registering with the aperture in said strip, a burner tip, and a pipe connecting said tip to the gas chamber of said generator and extending through such registering apertures. 105

7. In a portable lamp, the combination of a case; an apertured reflector; means mounting said reflector on said case comprising an apertured plate secured to said reflector, with such apertures in register; a perforated chimney communicating with the interior of said reflector through such apertures; and a cap mounted on said chimney. 115

8. In a portable lamp: the combination of a gas generator; an enclosed lamp house mounted on the front thereof; and a handle for said lamp secured to the front and rear sides of said generator and having portions thereof spaced from the top and rear side of said generator. 125

9. In a portable lamp: the combination of a gas generator; an enclosed reflecting 130

chamber comprising a transparent front wall and an apertured rear wall secured to said generator; a burner tip within said reflecting chamber and communicating with the gas compartment of said generator through said aperture; and a handle having a downwardly extending extremity attached to the front of said generator, and the other extremity extending upwardly and attached 10 to the rear of said generator.

10. A portable lamp comprising a casing, a lamp house on the front thereof and a handle, said handle extending upwardly from the front of said casing, rearwardly 15 above and spaced from said casing, downwardly behind and spaced from said casing and forwardly to said casing, whereby said handle may be gripped either above or behind said casing.

20. 11. In a portable lamp, the combination of a case carrying lighting means, a handle for said lamp comprising a metal strip se-

cured to said case near one end of said strip, said strip extending outwardly from said case below its connection thereto, a 25 plate secured to said strip and a reflector between said plate and the outwardly extending portion of said strip.

12. In a portable lamp, a combination of a case carrying lighting means, a handle for said lamp comprising a metal strip secured to the front of said case near one end of said strip, said strip extending outwardly from said case below its connection thereto, a plate secured to said strip above its connection to said case, a reflector between said plate and the outwardly extending portion of said strip, a cover for said reflector and means secured to said plate and said outwardly extending part of said strip for holding said cover against said reflector. 35 40

In testimony whereof, I affix my signature.

WILLIAM F. HUNT.
